UNITED STATES PATENT OFFICE.

EDWARD C. MOORE, OF YONKERS, NEW YORK, ASSIGNOR TO TIFFANY & CO.,
OF NEW YORK, N. Y.

DESIGN FOR PAPER-BOXES.

Specification forming part of Design No. 6,982, dated November 4, 1873; application filed August 4, 1873.
[Term of Patent 7 years.]

To all whom it may concern:

Be it known that I, EDWARD C. MOORE, of Yonkers, Westchester county, State of New York, have invented and produced a new and original Design for Paper-Boxes for Jewelry, &c., of which the following is a specification:

Figure 1 is a side view, and Fig. 2 an end view, of a box constructed according to my design, which consists of the rounded form of

the cover A A of box, as shown, for boxes made of stiff paper, bristol, or straw board.

I claim—

The design for jewelry boxes formed by the rounded form of the cover A A, substantially as described and illustrated.
